UNITED STATES PATENT OFFICE.

JOHN R. W. AMBROSE, OF TORONTO, ONTARIO, CANADA.

TRACK AND PLATFORM ARRANGEMENT FOR RAILWAY STATIONS.

Application filed January 23, 1928. Serial No. 248,788.

The principal objects of the invention are to obviate the extremely objectionable features of handling baggage and express on the platforms used by passengers in railway stations and to provide separate platforms giving access to opposite sides of the train without an objectionable use of space.

The principal feature of the invention consists in the novel formation of the platforms whereby passenger and baggage platforms are placed in an alternating arrangement, the passenger platforms being narrowed at the ends and the baggage platforms being widened correspondingly at the ends with the intervening tracks curved to correspond with the arrangement providing wide passenger areas accessible for the coaches and wide baggage platforms accessible to the baggage and express cars.

The accompanying drawing is a plan view of my improved arrangement of platforms and tracks.

In the handling of passenger traffic it is necessary to provide an ample width of platform to accommodate large crowds and I propose to construct the wide passenger platforms A of sufficient length to accommodate the average number of passenger cars. These platforms are narrowed at the ends to allow of access to all cars of any length of train but it will be readily understood that a narrow platform at the ends of a train will accommodate the passengers boarding or alighting from the end coaches.

The stairways or elevators B giving access to these platforms will be arranged centrally of the wider portion and the traffic will flow to and from this point without obstruction.

The tracks are curved to conform to the shape of the platform A and between each pair of tracks C is arranged a narrow platform D which is widened at the ends to form the baggage platforms E which will be as

wide as required to enable the expeditious handling of baggage and express, the narrow connecting portion D being of sufficient width to accommodate the trucks.

In an arrangement of tracks and platforms such as described the maximum areas are arranged in the necessary locations and the narrower portions are arranged where the wider accommodation is not required. The station area is thus conserved to the best advantage and an absolute division of the traffic is insured.

What I claim as my invention is:—

1. A track and platform arrangement for railway stations, comprising platforms having converging adjacent ends and tracks curved to pass between the convergent ends.

2. A track and platform arrangement for railway stations, comprising broad passenger platforms converging at the ends, tracks curved to conform to the convergent platforms, and baggage platforms having divergent ends approaching the convergent ends of the passenger platforms and conforming to the curvature of said tracks.

3. A track and platform arrangement for railway stations, comprising, broad passenger platforms converging at the ends, tracks curved to conform to the convergent platforms, and narrow baggage platforms widening out at the ends to conform to the curvature of the tracks at the convergent ends of the passenger platforms.

4. A track and platform arrangement for railway stations, comprising broad passenger platforms converging at the ends and having means of ingress and egress at the centre, tracks parallel with said platforms curved to conform to the converging ends thereof, and baggage platforms arranged between the diverging tracks and having means of ingress and egress in their wider portions.
